UNITED STATES PATENT OFFICE.

ROBERT B. BRITTON, OF EMPORIUM, PENNSYLVANIA.

CAR-JACK.

1,372,271.

Specification of Letters Patent. Patented Mar. 22, 1921.

Application filed July 12, 1920. Serial No. 395,567.

To all whom it may concern:

Be it known that I, ROBERT B. BRITTON, a citizen of the United States, residing at Emporium, in the county of Cameron, State 5 of Pennsylvania, have invented certain new and useful Improvements in Car-Jacks; and I do hereby declare the following to be a full, clear, and exact description of the invention, such as will enable others skilled in 10 the art to which it appertains to make and use the same.

This invention relates to new and useful improvements in jacks and particularly to car jacks.

15 One object of the invention is to provide a novel and improved jack by means of which the weight of a car can be raised from the axles so as to readily permit the opening of the journal boxes and the removal of 20 the brasses for renewing and repairs.

Another object is to provide a novel and improved device of this character by means 25 of which the removal and replacing of brasses can be accomplished at any point on a railway, without the necessity of taking the car to a round house or repair shop.

A further object is to provide a novel and improved device of this character which is 30 readily adaptable for use in connection with railways whether the rails thereof are of one weight or another, the variation in height, due to difference in weight, being compensated for by the adjustable feature of the leg of the jack.

35 Other objects and advantages will be apparent from the following description when taken in connection with the accompanying drawing.

In the drawing:

40 Figure 1 is a side elevation of the jack applied to the truck frame of a railway car, and with the truck frame elevated by the jack, the dotted lines indicating the position of the jack before the car has been moved to 45 the position in which the jack appears in full lines.

Fig. 2 is an edge elevation of the jack with the truck in section to show the clamps.

Fig. 3 is a perspective view of the jack re- 50 moved from the car.

When it becomes necessary to remove the brasses from the journal boxes of railway cars, the usual practice is to take the cars

to the shop, jack up the car, and then remove the brasses, for the purpose of replacing or 55 repairing them. This takes a large amount of time, and puts the cars out of use for a time. Also, the need for the change of brasses may occur at a point a considerable 60 distance from a repair shop. It is in this latter instance that the present invention is especially useful. The car can be readily jacked up, the brasses removed, and repaired, or replaced by new ones, and the 65 car permitted to continue its travel without the loss of but a short time.

Referring particularly to the accompanying drawing, 10 represents the head of the jack which is in the form of an elongated flat metal or other member, having on the 70 intermediate portion of its lower face a pair of parallel apertured lugs 11. Between these lugs is disposed the upper end of the leg 12 of the jack, a pivot pin or bolt 13 being engaged through the lugs and the upper 75 end of the leg, whereby the leg is mounted for pivotal movement. On each end of the member 10 are mounted the angular U-shaped members 14, the outer ends of the 80 legs of which are threaded for the reception thereon of the nuts 15. An elongated member 16, having openings in its opposite ends, is engaged on the legs of each U-shaped 85 member 14, and extends therebetween, the nuts 15 being engaged on said legs after the member is in position.

In the operation of the device, the nuts 15 and the plates 16 are removed from the legs of the members 14, the said members 14 engaged in straddling relation to the lower 90 longitudinal bar 17, of the car truck frame 18, and from therebeneath. The plates 16 and nuts are then applied to the legs of the members 14, and the nuts turned down to firmly clamp the device to the truck frame 95 bar. The outer or lower end of the leg 12 is then engaged on the upper face of the adjacent end of a tie 19. The car is then moved forward or backward, as the case 100 may require, with the result that the truck frame will be elevated from the axles, thereby permitting the brasses to be easily removed through the opening in the journal box. The brasses having been replaced by new ones, or repaired, the car is moved 105 again so as to lower the truck frame and

bring the brasses to bear on the axle ends. The nuts are removed the jack taken away. Thus a considerable amount of time and labor is saved, and the necessity of taking the car to the shop completely obviated.

In view of the fact that railway rails differ in weight per section, the size of the rail necessarily is different, thereby causing the cars to stand higher or lower with respect to the ties. To compensate for this variation in height of the rails, there is provided a detachable foot 20 having a recess 21 in its upper end for the reception of the lower end of the leg of the jack, a cross pin 22 being engaged through the leg and foot, as shown. This foot elevates the jack to the proper height for a rail and car which

will not accommodate the jack without the foot.

What is claimed is:

A car jack for facilitating the removal of car journal brasses comprising a head having yokes on the ends thereof, a plate for engagement on the arms of each yoke and clamping means for the plate, a leg pivotally connected to the lower side of the head, and a removable foot block for the lower end of the leg.

In testimony whereof, I affix my signature, in the presence of two witnesses.

ROBERT B. BRITTON.

Witnesses:

W. J. LEAVITT,
JETTIE L. CRAVEN.
